(57) **CLAIM**

The ornamental design for a faucet, as shown and described.

DESCRIPTION

FIG. 1 is a perspective view of a faucet, showing my new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan thereof;
FIG. 9 is an enlarged view of portion 9 shown in FIG. 2;
FIG. 10 is an enlarged view of portion 10 shown in FIG. 2;
and,
FIG. 11 is a perspective view of the design in an open status.
The broken line showing of the faucet is for the purpose of illustrating article and forms no part of the claimed design.
